Primary Examiner — Marie D. Fast Horse*Assistant Examiner* — Jennifer Sierra Yosinski(74) Attorney, Agent, or Firm — Ann K. Gallagher(57) CLAIM

The ornamental design for a caddy, as shown and described.

DESCRIPTION

FIG. 1 is a perspective view showing a new design for a caddy;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the caddy depicted in broken lines in FIGS. 3, 4, 5, and 7 form no part of the claimed design.
